SAFETY DEVICE FOR DRILL PRESS TABLES OR THE LIKE

Emil B. Guze, Chicago, Ill., assignor to F. & S.
Machine Tool Company, Chicago, Ill., a corpora-
tion of Illinois

Application August 2, 1943, Serial No. 497,037

2 Claims. (Cl. 77—55)

This invention relates to certain new and useful improvements in drill press attachments and more particularly to a safety device for drill presses or other machinery having an adjustable table or work plate and has for its principal object the provision of an improved construction of this character which will be highly efficient in use and economical in manufacture.

While I have illustrated my improved safety device in association with a drill press it is to be understood that the same may be used with other similar machinery having a work table. In drill presses of the type shown the work table is usually adjustable longitudinally with respect to a vertical column and secured thereto by a wedge screw. It is not infrequently that this screw, by reason of vibration, becomes loose and as a consequence the table gradually works itself down with respect to the column. Also it has been known that serious accidents have resulted because of dropping of the table by accident or careless workmen. It is therefore one of the salient objects of this invention to provide an attachment for a drill press in the form of a safety device which will function to prevent the accidental movement or dropping of the work table and one which will effectively hold the same against slippage due to shaking or vibrations.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view of a drill press showing my invention associated therewith;

Fig. 2 is a cross sectional detail view of the drill press column showing a plan view of the invention; and

Fig. 3 is a fragmentary sectional detail view taken substantially on line 3—3 of Fig. 2.

The drawing illustrates the preferred form of construction of my invention.

The usual and conventional drill press 9 includes a work table 10 carried by a sleeve 11. This sleeve 11 is movably mounted upon a column 12. This column 12 carries the operating mechanism including the driving motor 13 and the driver chuck 14 carrying the drill 15.

The sleeve 11 is usually secured in an adjusted position by a wedge screw 16 of the conventional construction including the operating handle 17.

It is with such a device that my safety attach-

ment is associated. The safety attachment includes a collar 18 comprising two sections 19 and 20. Each section is provided with lugs or ears 21 secured together by screw bolts 22 or the like whereby to securely attach the collar 18 to the column 12.

The collar section 20 is provided with a handle 23. Mounted on this handle 23 is a block 24. The forward end portion 25 of the block 24 is provided with a bore 26 terminating into a reduced bore 27 formed in the rearward portion of the block 24.

Mounted in the bore 26 is a bolt 28 having a flat surface portion 29 to provide a stop shoulder 30 adapted to be engaged by a stop pin 31 carried by the block.

The bolt 28 is freely mounted in the bore 26 and is urged outwardly by a spring 32 mounted in the bore 27. This arrangement is such that when there is no weight upon the collar the bolt 28 being projected against the column 12 will hold the collar in position upon the column. This permits the operator to adjust the table 10 without fear of the collar 18 dropping.

When the weight of the work table 10 is disposed upon the collar through the sleeve 11 and the block 24 the collar 11 will have a tendency to tilt. As a result the collar is in effect wedged upon the column 12 and therefore securely holds the work table in place.

From the above it is apparent that the construction of this invention is simple, economical and highly efficient in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A safety device for a machine having a column, a sleeve adjustable on the column, and a table carried by the sleeve, comprising a collar embracing the column with a portion engageable by the sleeve to effect wedging of the collar against the column by tilting of the collar under the weight of the sleeve and table, means for releasably holding the collar in a position upon the column when no weight is imposed upon the collar, said means comprising a bolt carried by

the collar and adapted to engage the column, and a spring means for pressing the bolt against the column.

2. A safety device for a machine having a column, a sleeve adjustable on the column, and a table carried by the sleeve, comprising a collar embracing the column, a block on the collar and engageable by the sleeve to effect wedging of the

collar against the column under weight of the sleeve and the table, means for releasably holding the collar in a position upon the column when no weight is imposed upon the collar, said means comprising a bolt carried by the collar and adapted to engage the column, and a spring means for pressing the bolt against the column.
